LOW TEMPERATURE CARBONIZATION
OVEN

Charles Honnay, Tieff, Belgium

Application May 9, 1931, Serial No. 536,288, and
in Belgium May 14, 1930

3 Claims. (Cl. 202—117)

This invention relates to a low temperature distillation or carbonization oven of the type in which the material fed a heated sole is simultaneously moved forward and ploughed by the means ensuring its progression. Its object is to allow of continuous and economical work on a commercial scale.

According to this invention, the coal or other material to be carbonized, is spread over the sole in an exceedingly thin layer the depth of which does not exceed 15 to 20 millimeters and it is ploughed or turned in such manner that the depth of coal remains substantially uniform throughout, i. e. so that no gaps leave the sole uncovered and no substantial accumulations are formed above the general level of the layer of coal.

To this end, the layer of coal or other material is ploughed or turned obliquely on the sole in zigzag fashion in such manner that it is prevented from heaping ahead of the ploughing devices and is caused to close up the furrows made by the latter in their progression.

Whilst the layer of coal is thus made to progress and to be ploughed or turned without any variation in its depth, it is subjected to perfectly uniform heating by the action of a large number of heaters distributed at regular intervals beneath the whole surface of the sole.

Immediately upon leaving the layer of coal, the volatile products distilled therefrom are filtered by a sieve placed adjacent to and above the sole in order to separate them from the dust which may be carried away with them. The gaseous products pass through said sieve and fill a chamber in which they impart some of their heat to a layer of coal spread upon a second sieve forming the roof of said chamber. They are then discharged, preferably under a slight vacuum, through pipes opening into the chamber comprised between the two sieves. The coal thus preheated by the gases feeds the layer undergoing distillation on the sole.

The oven for carrying out this process comprises a muffle chamber within which is driven an endless conveyor of wire gauze or perforated sheet metal fitted with transverse rows of obliquely placed scrapers arranged zigzag fashion.

The lower band of the conveyor rests upon the sole of the muffle chamber and its zigzag scrapers turn or plough the thin layer of coal under distillation, whilst its upper band carries the coal to be preheated, which is fed thereto in the form of a thin layer by a suitable distributor placed at one of its ends. The other

end of the upper band discharges the preheated coal to feed the layer under distillation on the sole. Together with the unheated side walls of the muffle chamber, the upper and lower bands of the endless conveyor enclose the chamber into which the distillates are released after passing through the lower conveyor band which acts as a dust sieve.

The sole is uniformly heated throughout its surface by a plurality of rows of gas burners regularly spaced and preferably arranged across it. The sole may consist of inverted U irons arranged lengthwise side by side, whose shanks are joined together and are notched at intervals to allow the sole thus assembled freely to contract or expand lengthwise without warping. For the same purpose, one end of the sole is supported by the rear wall of the muffle chamber in a joint of asbestos or other suitable material, whilst the outer shanks of the two U irons at the edges of the sole rest in asbestos lined grooves.

An oven according to the invention is illustrated by way of example in the accompanying drawings in which:

Fig. 1 is a general view of the oven in longitudinal section,

Fig. 2 is a transverse section of the oven on a larger scale,

Fig. 3 shows on a larger scale a section of the endless conveyor and sole in side elevation,

Fig. 4 is a plan view of the same section of conveyor and

Fig. 5 is a front view of the scrapers.

In the upper part of the brickwork 1 of the oven shown in the drawings is enclosed a muffle or distillation chamber 2 comprised between a roof 3, side walls 4, end walls 5, and a sole 6 which separates it from a heating chamber 7 extending throughout its length.

Within the muffle or distillation chamber 2 is an endless conveyor 8 travelling round chain-wheels 9, 10 mounted on cross-shafts 11, 12 one of which is driven by motor 13 through reducing gears 14, 15 whilst the other is drawn by two weights 16 whose function is to keep the conveyor taut. These weights 16 act upon slides 17 carrying shaft 12 in guideways 18. The frame of the endless conveyor consists of two endless chains 19 and of T iron cross members 20 which connect the chains at intervals and are attached to their carrying links by angle-pieces 20'. Panels of wire gauze stretched between the cross-members 20 are attached to the webs of the T irons and form the actual conveyor band.

Each crossmember 20 of the endless conveyor

carries a row of thin, rectangular scrapers 22 clearly shown in Figs. 3 to 5. Fishplates 23, to which the scraper blocks 22 are fastened in groups by stems 24, grip the webs of the cross-members 20 to which they are attached by bolts 25. All the scraper blocks 22 are arranged obliquely relatively to the crossmembers 20, those of one row pointing one way and those of the following row pointing the other way. They form a zig-zag pattern along conveyor 8 and are preferably staggered (Fig. 4).

The upper band of conveyor 8 travels on rails 26 which prevent sagging and are carried by cross girders 27 anchored in the side walls 4 of muffle 15 chamber 2. The scrapers 22 of the lower conveyor band rest upon the sole 6 which they scrape throughout its length and width.

The sole 6 consists of a plurality of inverted U irons 28 whose sides are in mutual contact and joined together by bolts or rivets 29. Triangular notches 30 are cut alternately in one and other side of each U iron in such manner as to avoid weakening the same. By this means the sole is allowed to expand or to contract under heat 25 without buckling or warping. Provision is made for longitudinal expansion by freely resting one end of the sole loosely in a socket 31 of one end wall 5 of muffle chamber 2. This socket is stuffed with flake asbestos or other suitable material and the outside shanks of the U irons edging the sole also bear loosely in two grooves 32 contained in the sidewalls 4 and filled with suitable stuffing materials. The fixed end of the sole is anchored at the front end of the furnace 35 in a low wall 33. A discharge hopper 34 fills the space between wall 33 and the other end wall 5 and opens into a pit 35, below the level of muffle chamber 2.

The heating chamber 7, extending beneath sole 40 6, contains a large number of closely arranged regularly spaced cross lines of gas burners 36, fed from a main pipe 36' which is arranged outside the furnace and may be supplied with some of the gases distilled in the latter. The whole 45 of the sole 6 whose heating surface is increased by the depending shanks of the U irons 26, thus is very evenly heated by the small close-set gas flames of gas lines 36.

Adjoining the oven above described is a coal 50 dryer, not shown, which may conveniently be heated by waste gases issuing from heating chamber 7. The coal or other material to be distilled leaves this dryer at a temperature of approximately 200° C. and is conveyed by suitable means 37 to a distributor 38 of the endless belt type, which feeds it to the front end of the upper band of conveyor 8 in the form of a continuous thin layer, approximately 15 to 20 millimeters in depth. The conveyor slowly carries 55 towards the back of muffle chamber 2 the layer of coal which, as the conveyor 8 passes round the wheels 9, is transferred on to the sole 6. A curved plate 39 prevents the coal from heaping in the angle of the muffle chamber.

On the sole 6 the layer of coal is ploughed and slowly propelled towards hopper 34, its depth being kept at 15 to 20 millimeters. The ploughing is effected by the scrapers 22 of lower conveyor band 8, which simultaneously propel the coal forward and laterally in a series of alternating slants corresponding with their own oblique positions and each fragment of coal is thus made to progress along the sole in a series of zigzag courses. 70 In addition to effectively stirring the coal and lengthening its course of travel along the sole,

this zigzag ploughing process has the added advantage that the coal thrown to one side by the oblique face of a scraper immediately fills the furrow by the adjoining scraper and the sole is never left uncovered as would happen if the scrapers were placed at right angles to the direction of progression. Deposits of graphite on the sole and their resulting inconvenience are thus avoided.

The scrapers 22 are preferably shallow, their height not exceeding that of the coal layer, so as to preclude the heaping of coal ahead of them and, as no gaps are left behind them the depth of the layer remains substantially uniform in spite of the intense ploughing to which it is subjected.

The temperature maintained throughout the sole 6 by the burners 36 is preferably about 650° C. so that the maximum temperature of the coal on the sole is 500° C. The temperature of the distilled gases does not exceed 450° C.

As the distilled gases are evolved from the coal under the combined action of heat and ploughing, they escape through the wire gauze panels 21 of the lower conveyor band which retain any dust carried thereby. The filtered gases issue into space 40 enclosed between the two bands of conveyor 8 and they are discharged, preferably under a slight vacuum, through pipes 41 opening in the side walls 4 of the muffle chamber and led outside the furnace to a collector 42. In passing through inner chamber 40, the distillation gases heat, through the wire gauze of conveyor 8, the layer of coal spread upon the upper band of the same and raise its temperature to 300° C. approximately, a substantial part of their heat thus being recuperated.

Decomposition of the tar is precluded owing to the fact that the gases are evacuated so soon as they are freed, and it has been found that the phenol content of the tar obtained by this process does not exceed 25%. Owing also to the filtering of the gases through the gauze conveyor, the percentage of coal dust in the tar does not exceed 1/2%, whereas it has reached as much as 30% in some of the ovens proposed heretofore.

The semi coke resulting from the carbonization drops from the end of the sole 6 into hopper 34 and thence into a watertight pit 35, where the remaining tar imparts thereto the consistency of a paste which may then be immediately pressed into agglomerates, without the use of binding materials. It may also be discharged, without treatment, by any suitable means.

A distillation oven as above described may be started in a few hours and remain in continuous service for several months without being extinguished for repairs or cleaning. Its normal hourly output is about 100 kilos of semi-coke per square meter of heated surface.

It will be understood that the invention is not restricted to the constructional details herein described and illustrated by way of example in the accompanying drawings and that the construction may be varied without departing from the scope of this invention as set forth in the appended claims.

I claim:

1. In a low temperature distilling and carbonizing oven, the combination with a chamber, of an endless band sieve mounted for rotation around horizontal axes in said chamber; said sieve comprising an upper portion and a lower portion substantially parallel to each other, means for moving said sieve, rows of scrapers arranged exteriorly on said portions obliquely to the direc-

- tion of movement of said sieve, means for feeding material to be treated to said upper portion, a sole in the chamber under said sieve adapted to receive material discharged from the sieve, said 5 scrapers being adapted to plough the material on said sole, means for subjecting the sole to substantially uniform temperature throughout its area, and a gas offtake pipe communicating with said chamber between the upper and lower portions of said sieve.
2. In a low temperature distilling and carbonizing oven, the combination with a chamber having side walls and a sole, of an endless band sieve mounted for rotation around horizontal axes in 15 said chamber, said sieve comprising two superposed parallel portions being adapted to filter gas distilled from material on said sole, rows of obliquely arranged scrapers secured exteriorly to said sieve, a gas offtake pipe opening above the lower portion and below the upper portion of said 20 sieve, means for feeding material to be treated on said upper portion and thence to said sole, means for uniformly heating said sole over its entire surface, one end of said sole being anchored to one wall of said chamber only.
3. In a low temperature distilling and carbonizing oven, the combination with a chamber having side walls and a sole, of an endless band conveyor in said chamber having upper and lower superposed horizontal portions, said conveyor portions each having a foraminous endless carrying surface, a pair of endless chains adjacent the edges of said carrying surface, and transverse members secured to said chains; rows of scrapers secured to each of said transverse members, said scrapers projecting away from the said carrying surface and comprising each a shallow body portion arranged at an acute angle to the direction of travel of said conveyor and each scraper having a stem portion secured to one of said transverse members, means for moving said conveyor, means for discharging material to be treated onto said upper portion, said conveyor being adapted to discharge material onto said sole, said scrapers being arranged to plough over said sole when passing thereover, and offtake means for evacuating gas from the space in the chamber between said two portions of the conveyor.
